(No Model.)

J. HYLAND.

TUBE AND PIPE CUTTER, BEADER, AND EXPANDER.

No. 441,566.

Patented Nov. 25, 1890.

UNITED STATES PATENT OFFICE.

JOSEPH HYLAND, OF CHARLEVOIX, MICHIGAN, ASSIGNOR OF ONE-THIRD TO
ALBERT E. MASON, OF SAME PLACE.

TUBE AND PIPE CUTTER, BEADER, AND EXPANDER.

SPECIFICATION forming part of Letters Patent No. 441,566, dated November 25, 1890.

Application filed April 5, 1890. Serial No. 346,661. (No model.)

To all whom it may concern:

Be it known that I, JOSEPH HYLAND, of Charlevoix, in the county of Charlevoix and State of Michigan, have invented a new and 5 Improved Combination Tube and Pipe Cutter, Beader, and Expander, of which the following is a full, clear, and exact description.

The object of the invention is to provide a new and improved combination-tool for conveniently and rapidly cutting pipes or tubes, expanding the same, and forming a bead thereon, as desired.

The invention consists of a tapering spindle provided with longitudinal dovetailed 15 grooves, a cylinder held to slide on the said spindle and provided with expanding-rollers, and cutting and beading tools held to slide in the said cylinder and having dovetails fitting into the said longitudinal grooves.

20 The invention also consists of certain parts and details and combinations of the same, as will be hereinafter fully described, and then pointed out in the claims.

Reference is to be had to the accompanying 25 drawings, forming a part of this specification, in which similar letters of reference indicate corresponding parts in all the figures.

Figure 1 is a side elevation of the improvement. Fig. 2 is a plan view of the same. Fig. 3 is a sectional side elevation of the same on the line *x x* of Fig. 2. Fig. 4 is a transverse section of the same on the line *y y* of Fig. 3. Fig. 5 is a like view of the same on the line *z z* of Fig. 3. Fig. 6 is a similar view of the 35 same on the line *w w* of Fig. 3. Fig. 7 is an end elevation of one of the outside knives. Fig. 8 represents detailed views of one of the inside knives. Fig. 9 is a perspective view of a dummy knife. Fig. 10 is a plan view, 40 with parts in section, of the device for turning and guiding the spindle. Fig. 11 is a perspective view of a spring-plate for the knives. and Fig. 12 is a face view of the spindle-nut.

The combination tube and pipe cutter, 45 beader, and expander *A* is provided with a tapering spindle *B*, having on opposite sides longitudinally-extending dovetails *C* and *C'*, and also provided on its large end with a head *B'*, adapted to be turned by a suitable tool or 50 means hereinafter fully set forth.

The spindle *B* passes loosely through a cylinder *D*, having on one end a slightly-dished flange *E* and containing a series of expanding-rollers *F*, each of which is provided with an annular recess *F'* and adapted to travel on 55 the outside of the spindle *B*. Each of the rollers *F* is provided with trunnions *F''*, fitted to slide in radial grooves or slots arranged in a cylinder *D*, so that the said rollers are moved outward when moving the spindle *B* through 60 the cylinder *D* from its small end toward the large end. In order to conveniently hold the rollers *F* in position on the cylinder *D*, the latter is provided with a head *D'*, bolted or otherwise fastened on arms *D''*, forming 65 guideways or recesses for the reception of the rollers *F*. The latter are each provided with an annular recess, which is designed to form a shoulder on each side of head of boiler when expanding the boiler-tube, the shoulders 70 forming a brace for the boiler.

In order that the rollers, while passing over the longitudinal dovetailed grooves *C* and *C'*, may be held outward when the spindle is passed through the cylinder *D*, as previously 75 mentioned, dovetails *G* are fitted into the said dovetailed grooves under the said rollers, as is plainly shown in Figs. 3 and 6. When the spindle is passed through the cylinder, all the 80 rollers move simultaneously outward as the spindle *C* increases in diameter.

In the head *D'* of the cylinder *D* are fitted to slide in suitable radial grooves the inner cutters *H*, each of which is provided with a dovetail *H'*, (see Fig. 8,) fitting into the corresponding dovetailed grooves *C* or *C'*, arranged in the spindle *B*. Thus when the latter is moved through the cylinder *D* from its smaller end toward its larger end the dovetails *H* travel in the said grooves and move 85 the cutters outward. At the same time that the spindle *B* is turned the cylinder *D* is carried with it, as the dovetails *H* engage the grooves *C* and *C'*. The cutters *H* thus cut into the pipe or tube in which the device is 90 used as the spindle is moved farther through the cylinder *D* and is turned at the same time. To assist in drawing the cutters back from the cut, a spring-plate *H''* is placed on 95 the inner end of the cutter above the dove- 100

tail H', the said plate resting on the inside of the cylinder D.

In order to form a bead on the end of the tube or pipe, grooved rollers I are employed, 5 mounted to turn on radial shafts having their bearings in brackets J, each fitted to slide radially in a corresponding groove E', formed on the inner face of the flange E, secured on the upper end of the cylinder D. Each of 10 the brackets J is provided at its inside with a dovetail J', fitting into the corresponding dovetailed grooves C or C', so that when the device is used as a beader and the spindle B is pushed through the cylinder and turned at 15 the same time the said cylinder is turned with the spindle as the dovetails J' engage the corresponding dovetailed grooves C and C' of the spindle B.

In order to cut a pipe or tube preparatory 20 to bending where it projects too far beyond the outer side or face of the boiler or flue head, the brackets J, carrying the beading-rollers I, are removed and cutters K are inserted in the corresponding slots formed in 25 the cylinder D, each cutter being circular and mounted to turn in a frame K', having a dovetail K², adapted to engage the correspondingly-shaped dovetailed grooves C or C' in the spindle B.

30 In order to conveniently remove or insert the cutters H and K and the beader-rollers I, with their brackets J, each dovetail groove C or C' is provided at the small end of the spindle B with an enlargement C², and a similar 35 enlargement C³ is formed at the large end of the spindle B in the said groove. Now, when the operator desires to change the beading-rollers I for the cutters K the cylinder D is moved onto the large end of the spindle B, so 40 that the dovetails J' of the brackets J pass into the enlarged recesses C³, thereby permitting of removing the brackets J from the head D and inserting the bracket K' and cutters K in place, so that the dovetails K² pass into 45 the recesses C³, and when the head D' is now slid toward the small end of the spindle the said dovetails K² engage the correspondingly-shaped grooves C and C'. In a similar manner the bracket K' and cutters K can be ex- 50 changed again for the brackets J with the rollers I, as described.

For removing the inside cutters H the cylinder D is moved to the small end of the spindle B until the dovetails H' of the said cutters engage the recesses C² in the grooves C and C', so that the said cutters can be taken out and dummy cutters K³ can be substituted, so as to fill up the openings in the head D' previously occupied by the cutters H.

60 In order to conveniently turn the spindle B and to gage the same, the following device is provided: In the head B' of the spindle B are formed transverse openings, one of which can be engaged at a time by a pin L, held in 65 a U-shaped arm N, in the middle part of which is mounted to turn one end of a screw-rod O, screwing in a U-shaped frame P and pro-

vided at its outer end with a head O', adapted to be turned by means of a wrench or other suitable tool. In the legs of the U-shaped frame P are fitted to slide the rods Q, extending in line with the axis of the spindle B and adapted to be fastened in any desired position by the set-screws R.

When the device is used for cutting at a 75 certain distance on the inside of the pipe or tube, then the rods Q are adjusted in the legs of the frame P until the cutting-tools are in the proper position, after which the rods Q are fastened in place by the set-screws R, the inner ends of the said rods resting against the boiler-plate. The operator then turns the head O', and the screw O screws in the said frame P and pushes in the spindle B, so that the cutting-tools or the rollers are caused to 80 slide outward to cut or expand the tube. It will of course be understood that before the screw can exert this pushing action the inner cutters H or the dummies K³, as the case may be, must be thrown outward into firm engagement with the interior of the tube, and then when the screw is turned in the proper direction its tendency will be to draw the frame P toward the boiler-head. This device is also designed to draw back the spindle, so as to 85 let the knives down from the cut in case they get stuck therein, so as to not break off the end of cutting-tools.

It is understood that when the device is used only for cutting a tube on the inside the cutting-tools H are inserted in the head D' of the cylinder D and the spindle B is turned and at the same time pushed inward, so as to feed the cutting-tools against the inside of the pipe until the latter is cut. When the pipe is to 105 be cut near its outer end, then the cutting-tools K are inserted in place of the brackets J, and the above-described operation is repeated—that is, the spindle B is turned and pushed inward to feed the circular cutters 110 outward. When the outer end has been cut off, the cutters K are removed, and the brackets J, with the beading-rollers I, are inserted inside, and then the spindle B is again turned and pushed inward, so as to force the rollers 115 I, with their grooves, in contact with the cut edge of the pipe or tube, so as to form a bead thereon.

In order to prevent the head D from sliding off the spindle B, the latter is provided at its 120 smaller end with a reduced screw-thread B², on which screws a nut S' against the collar S, abutting against the small end of the spindle B, as is plainly shown in Fig. 1. This serves to prevent the cutting-tools and dummy 125 knives from being displaced from the spindle when the latter is pulled forward in the tube. The nut and washer may be formed in one piece, and on the washer are pivoted the drop stops or closures S², adapted to fold over the 130 slots of the spindle and to cover the said slots to keep the cutters in proper place. In order to remove the cutters, the stops or closures are opened.

Having thus fully described my invention, I claim as new and desire to secure by Letters Patent—

1. The combination, with the tapering spindle having a cylinder sliding thereon and turning therewith and tools projecting from the said cylinder into engagement with the tapering surface of the spindle to be projected outward thereby, of a separate and independent frame to rest against the boiler-head, and a screw turning in the said frame and connected at its inner end with the outer end of the spindle, substantially as described.

2. The combination, with a pipe cutter or expander provided with radially-sliding tools and a tapering spindle on which the tools slide and with which they turn, of a separate and independent frame to bear on the outer side of a boiler-head and having a screw mounted in it and connected at its inner end with the outer end of the spindle to simultaneously rotate and slide the spindle, substantially as described.

3. In a pipe cutter or beader, a sliding and rotating spindle, in combination with a **U**-shaped frame provided with parallel extensible rods, and a central rotary parallel screw connected at its inner end with the spindle to simultaneously rotate and impart longitudinal movement thereto, substantially as described.

4. In a pipe cutter or beader, the frame P, having a central spindle-operating screw O, provided at its inner end with a yoke N, having a transverse pin L, substantially as described.

5. In a pipe cutter or beader, the **U**-shaped frame P, having the parallel extensible rods Q Q in its two legs, and the central spindle-operating screw O, parallel therewith and provided at its inner end with a yoke N, having a transverse pin L, substantially as described.

6. A combined pipe cutter, expander, and beader consisting in a longitudinally-grooved tapering spindle, a cylinder sliding thereon and turning therewith, and provided between its ends with longitudinal slots and openings at opposite ends of said slots, annularly-grooved rollers extending through said longitudinal slots to expand the pipes at both sides

of the boiler-head and projected outward by the inward movement of the spindle, removable tool-carrying brackets working in the outer cylinder-openings and engaging the said spindle-grooves, and removable tools projecting through the inner cylinder-openings and engaging at their inner ends said spindle-grooves, substantially as set forth. 55

7. The combination, with the spindle having longitudinally-extending dovetail or undercut grooves terminating at both ends in enlarged openings or recesses, of the cylinder having inner and outer removable sets of tools provided at their inner ends with dovetail projections engaging the said grooves, 60 whereby when the cylinder is slid outward the outer sets of tools may be removed from or inserted into engagement with the spindle-grooves by means of the outer enlarged recesses, and when the cylinder is moved oppositely over the other recesses the inner sets of tools may be similarly operated, substantially as described.

8. The herein - described longitudinally-grooved spindle having enlarged recesses at 75 the inner ends of its grooves and pivoted stops or closures therefor, substantially as set forth.

9. The herein - described longitudinally-grooved tapering spindle having enlarged recesses at the inner ends of its grooves, a washer S on the inner end of the spindle, provided with pivoted stops or closures S', and the nut S', substantially as described. 80

10. The combination, with the tapering 85 spindle having longitudinal dovetail grooves provided at their outer ends with recesses C³, of the cylinder carrying the expanding-rollers F, provided with dovetails G, engaging said grooves, openings through the cylinder 90 near its outer end, and removable and interchangeable tool-carrying brackets, the inner ends of which are adapted to be passed through said openings into the recesses C³ and then into the dovetail grooves, substantially as described. 95

JOSEPH HYLAND.
